EMIL C. HOPPE, OF ELIZABETH, NEW JERSEY

DEVICE FOR AERATING LIQUIDS

Application filed May 31, 1930. Serial No. 457,954.

This invention relates to devices for aerating liquids, and is particularly intended for the use of preparing sparkling beverages.

While devices of this sort are generally known to be in use, my invention resides particularly in the construction and design of parts adapted to facilitate the aerating operation of liquids contained in bottles without undue loss of the liquid itself when containers or bottles are changed.

The object of my invention is to provide a device which will facilitate aerating liquid in containers, bottles, and the like, without spilling and wasting the liquid to be aerated when such containers are successively inserted into and removed from the device during the aerating operation.

The foregoing and further objects will be more fully apparent from the following description and the accompanying drawing, forming part of this disclosure but by no means intended to limit same to the actual showing, and in which

Figure 1 is an elevation of my device.

Figure 2 is a detail cross sectional view, taken on a plane perpendicular to the plane of a drawing.

Figure 3 is a detail cross sectional view, taken on a center plane coinciding with the plane of the drawing, and

Figure 4 is an enlarged cross sectional view in more or less diagrammatical form, taken on line 4—4 of Figure 2.

In the figures, numeral 10 denotes a base in which is fastened a hollow standard 11 provided at its lower end with a T connection 12, to which is preferably attached a pipe 13, through which the gas is passed into hollow standard 11. At the top of the standard there is provided a union connection, indicated at 14, clearly shown in cross section in Figure 2. Extending from union 14 is a pipe 15 which terminates in another union 16 attached to valve chamber 17 shown in Figure 3. The gas, as for instance, carbonic acid, or the like, enters through pipe 13 and passes into standard 11 and through pipe 15 into valve chamber 17, where its outlet is controlled by gas valve 18. Valve chamber 17

50 forms the portion of a body 19 which is held

in place by means of a bracket 20, provided with a collar 21, which latter is secured to standard 11 by means of set screw, indicated at 22.

Body 19 is provided with a cup-shaped outwardly threaded upper portion 23, to which is preferably attached, by means of nut 24, a gas chamber 25. The latter is provided with a cap 26 to which is attached a gauge 27, indicating the amount of pressure of the gas entering the machine. The lower part of body 19 is also threaded, as indicated at 28, and is engaged by internally threaded bushing 29, which clamps between body 19 and the flange of the bushing, a rubber member 30. This rubber member forms a ring-shaped cushion with a central opening 31. This cushion is intended to provide a seal between a container, in this case a bottle 32, and the interior of the device. The bottle rests upon an adjustable table 33, which may be readily elevated by means of a threaded spindle 34, operated by wheel or handle 35. By elevating table 33, the neck of the bottle is pressed tightly against rubber cushion 30. Table 33 is supported by means of a bracket 36, which may be set to any desired position by a set collar 37, securable to standard 11 by means of set screw 38. Thus the proper elevation of the table is attained, depending upon the height of the container to be inserted into the machine.

Around the bottle 32 will be seen screen or shield 39, suspended by means of a clamp bracket 40. This screen or shield may be adjusted relative to the bottle and may be elevated or lowered when bottles are changed.

The construction of body 19 contains all controls necessary for supplying gas to the container, permitting the release of gas when the container is removed from the machine and also permitting the draining of cylinder 25 when the liquid pressed thereinto, by the pressure of the gas, becomes excessive.

As will be seen from Figures 2, 3 and 4, body 19 is provided with the passage 41, controlled by valve 18, which first extends horizontally into the center of the body and then continues vertically downwards through the center thereof. The end portion of the ver-

tical passage is threaded, and attached to the threaded portion is a tube 42 extending downward into the liquid contained in bottle 32.

Another passage is formed in the body and clearly seen in Figure 3 at 43. This passage runs partially horizontally and partially vertically upwards and is controlled by release valve 44. To the threaded vertical portion of the passage is attached a vent or release tube 45 which extends into the cap 26 of cylinder 25. There is another vertical passage provided through body 19 and indicated at 46. This passage communicates between bottle 32 and cylinder 25.

The top portion of this passage is provided with a seat for a check valve or ball, indicated at 47, which prevents liquid from leaving cylinder 25 when bottle 32 is removed from the machine. Ball 47 is housed in a cage, indicated at 48, to prevent the ball from displacement and keeping it constantly in its seating position.

When gas is supplied through valve 18 and passes through tube 42 into the container, the liquid therein will rise and some of it will pass through passage 46 into cylinder 25. In passing, thus, the liquid has to lift ball or check valve 47, which immediately seats itself when the pressure from below ceases. Thus, when the liquid in the container is sufficiently charged and then the bottle is removed, no liquid contained in the cylinder 25 is permitted, due to check valve 47, to spill or otherwise leave the cylinder.

When the liquid in the cylinder reaches such a height that it would pass down through exhaust tube 45, when valve 44 is operated, it becomes necessary to release the liquid from cylinder 25, which is done by means of valve 49, seen in Figures 1 and 2. This valve is connected by means of a passage 50 running partially horizontally and partially vertical, and terminating at the bottom of the hollowed-out portion of body 19, which portion communicates with cylinder 25.

By preventing the spilling and waste of the liquid, my device becomes not only more economical, but more practical and cleaner in operation.

Operation

The use of my device is rather simple; pipe 13 is connected to a bomb or container filled with gas with which a liquid or beverage is to be charged. A number of bottles are filled with the beverage and successively clamped into position by means of first releasing and then elevating table 32, by turning the hand wheel 35. When the bottle is in place and tightly presses with its neck portion against rubber cushion 30, valve 18 is opened and the charging gas is permitted to enter the liquid through pipe 42 extending into the bottle.

When the gauge indicates a sufficient pressure considered safe as to the tensile strength of the container, valve 18 is closed. Before removing bottle 32, valve 42, which releases the gas from cylinder 25 through pipe 45, is opened. Now the bottle is removed and another bottle inserted in its position. After a period of thus charging the liquid of numerous bottles, the excessive liquid gathering in cylinder 25 is released by means of valve 49.

Having thus described my invention, be it understood that while I have shown specific constructions in the drawing, that changes and improvements may be imparted therein without deviating from the broad scope of my invention, for which I claim:

1. A liquid aerating device, comprising in combination, a base, a hollow standard extending therefrom, a pipe connection leading into said standard, a control body associated with the upper portion of said standard and containing a gas intake passage, a gas outlet passage and a liquid discharge passage, all of said passages provided with control valves, a through passage transversing the body in substantially vertical direction and provided with a check valve for preventing liquid from passing downwards through the body while permitting it to pass upwards, a cylinder mounted on top of the body and provided with a gas pressure indicating gauge, a resilient container seal provided at the bottom of said body, said gas intake passage having a connection with said hollow standard, a charging pipe extending from said intake passage downwardly through said container seal and adapted to enter a container placed into the device, a gas discharge pipe connected with and extending from said gas discharge passage into the upper portion of the interior of said cylinder, said liquid discharge passage connecting with the lower cylinder portion, a container supporting and locking table adjustably associated with said hollow standard, means for raising or lowering said table provided with the latter, and an adjustable screen or safety guard associated with said hollow standard and adapted to house a container placed upon said table.

2. In a liquid aerating device, the combination with a base, of a hollow standard extending therefrom and adapted for conveying gas, gas intake means provided at one end of said standard, gas discharge means secured at its other end, gas and liquid control means connected with said discharge means and removably associated with said standard, and adjustable container supporting means removably and adjustably mounted with said standard and adapted to facilitate pressing a container, the content of which is to be aerated, against said gas and liquid control means.

3. In a liquid aerating device, the combination with a base supported, hollow standard, of gas and liquid control means adjustably mounted upon said standard and connected with its hollow interior, said control means
5 comprising a body provided with a valve controlled intake passage adapted to convey gas into a container, the content of which is to be charged, a liquid retaining cylinder connected with said body, a valve controlled passage provided in said body and extending into said cylinder and adapted to release excess liquid from such container into the cylinder, a valve controlled gas discharge passage provided in said body and connected with
10 the upper portion of said cylinder, and a valve controlled liquid discharge passage connecting with the lower portion of said cylinder.

20 In testimony whereof I affix my signature.
EMIL C. HOPPE.
